The ornamental design for a handle for a folding knife, as shown and described.

DESCRIPTION

FIG. 1 is an isometric view taken from the upper left rear of a handle for a folding knife including my new design, wherein the broken line depiction of a pivot pin, a portion of a latch and a blade is included for illustrative purposes and forms no part of the claimed design;

FIG. 2 is an isometric view from the upper left rear of the handle for a folding knife shown in FIG. 1, showing my new design;

FIG. 3 is a left side elevational view thereof, the right side elevational view being a mirror image thereof;

FIG. 4 is a top plan, or back, view thereof;

FIG. 5 is a bottom plan view thereof;

FIG. 6 is a front, or blade, end view thereof; and,

FIG. 7 is a rear end view thereof.
